nium from a fused bath containing uranium halide and in the presence of uranium carbide.

2. The process which comprises electrodepositing uranium from a fused bath containing uranium halide and an alkaline earth metal halide in the presence of uranium carbide.

3. The process which comprises electrodepositing uranium from a fused bath containing uranium halide and an alkali metal halide in the presence of uranium carbide.

4. A continuous process for electrodepositing uranium which comprises conducting the electrolysis from a bath containing a uranium halide and sodium chloride in the presence of uranium carbide.

5. A process of forming a uranium salt which comprises subjecting uranium carbide to anodic treatment in a fused light metal halide bath.

6. A continuous process for electrodepositing uranium which comprises conducting the electrolysis from a bath containing uranium tetrafluoride in the presence of uranium carbide.

5 7. A continuous process for electrodepositing uranium, which comprises subjecting an electrolysis bath containing a uranium halide and a halide of light metal maintained between 500° and 800° C. to a voltage of 1-30 volts and a current density of 0.1-5 amperes/cm.² in the presence of uranium carbide.
